UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,122,538.

Specification of Letters Patent. Patented Dec. 29, 1914.

Application filed September 10, 1913. Serial No. 789,083.

To all whom it may concern:

Be it known that I, JOHN R. ROGERS, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal 15 to form a slug or linotype against the matrices which produce the type characters thereon, and the matrices thereafter returned through distributing mechanism to the magazine from which they started.

20 More particularly, it relates to such machines when equipped with a plurality of fonts of matrices, any selected one of which may be brought into action as desired.

In the commercial "Model 8" linotype, a 25 plurality of magazines are movably mounted so that any one may be brought into operative relation to the assembling devices at will; and in the commercial "Model 9" linotype, a plurality of magazines are arranged in fixed position, and the assembling devices are shiftable so as to be brought into operative relation to any one thereof. The present construction differs from both in that, while a plurality of magazines is still employed, they are not movable as a whole, nor are the assembling devices shiftable, so as to bring a particular one into action. There is but one operative position, which 35 position is fixed and successively occupied by the desired magazines, the several magazines being simply stored in the machine and made readily interchangeable by means for sustaining them during the interchange.

In other words and more specifically, these means permit the ready endwise removal of 50 the operative magazine, its temporary support, and its endwise transfer to an inoperative position in storage, and its replacement by another magazine, which reversely is withdrawn endwise from its storage position, supported, and then moved endwise into the operative position previously occupied by the first magazine.

In the accompanying drawings, I have shown my invention in preferred form and 60 by way of example, and as applied to a linotype machine, but obviously many changes and variations may be made therein, and in its mode of application, which will still be comprised within its spirit. Thus, it may 65 be similarly applied to other forms of typographical machines, such as typesetters, typecasters, and the like, which handle types or dies, instead of matrices. Generally speaking, I desire it to be understood that 70 I do not limit myself to any specific form or embodiment, except in so far as such limitations are specified in the claims.

Referring to the drawings: Figure 1 is a side view, partly in section, of a linotype 75 machine embodying my invention, the side of the magazine frame being broken away to expose its interior construction; Fig. 2 is a section on the line 2—2 of Fig. 1; Fig. 3 is a bottom view of one of the magazines; 80 Fig. 4 is a view similar to Fig. 1, illustrating a modification; Fig. 5 is a side view of the magazine frame, etc.; and Fig. 6 is a sectional detail on the line 6—6 of Fig. 5.

Referring first to Figs. 1, 2 and 3, the 85 three magazines A, A¹, A², are arranged in superposed position, the upper magazine A being in operative relation to the assembling devices B, and the release and delivery of the matrices therefrom being effected 90 from the keyboard B¹, all in the usual manner. Each of the magazines is provided with an entrance B², so constructed and mounted as to receive the matrices from the distributing mechanism B², when the magazine 95 is in action. The three magazines are

2

mounted in the frame C, which is pivoted at D to the main frame and is normally supported by suitable abutments D¹. It will be observed that the magazine frame C is provided with oppositely located grooves C¹⁰, formed in the inner sides thereof, and adapted to receive the end of the supporting bars A¹⁰ connected to the several magazines, and to permit their ready removal and replacement when desired. The grooves of the uppermost pair are somewhat longer than the other grooves, in order to allow the uppermost magazine to extend forwardly into relation to the assembling devices B. It will also be observed that the number of pairs of supporting grooves is one more than the number of magazines contained in the frame, in order to permit the free interchange of magazines. In the present instance there are four pairs of grooves and three magazines, the vacant pair being designed to receive the operative or top magazine when the latter is withdrawn from operative position, after which another magazine is withdrawn from its place of storage and transferred to the operative position. Means are provided in connection with the frame C to simplify and expedite the interchange of magazines therein. As shown in Figs. 1, 2 and 3, these means comprise a framework, consisting of the rock shaft E suitably journaled at the rear corners of the frame C and carrying the arms F, which in turn are provided with the anti-friction rollers F¹. Also connected to the frame is the operating arm G, provided with the locking device G¹, adapted to engage the fixed toothed sector G² and thus hold the arms F in different adjusted positions. The rock shaft E is also formed with a flanged roller E²⁰ adapted to engage and guide the longitudinal bar A²⁰ on the bottom of the proximate magazine, as the latter is moved to and from its position in the frame.

The method of interchanging the magazines is well indicated by dotted lines in Fig. 1. The frame C is first tipped rearwardly about its pivot D until it rests upon the frame abutments D², it being held thereby in a horizontal position. The handle G is then manipulated to swing the arms F about their pivotal center to their extreme uppermost position, in which they are held by the engagement of the locking device G¹ with the sector G². The operative magazine A is then withdrawn endwise from the frame C over and along the supporting arms F, when the arms are lowered to their lowermost position and locked therein, and the magazine is transferred endwise into the lowermost space in the frame C. By the further manipulation of the arms F, and a reversal of the previously described operation, another magazine A¹ or A² is with-

drawn from the frame, and then lifted into registration with the uppermost pair of grooves C¹⁰ in the frame, when it is moved longitudinally into operative position.

Figs. 4, 5 and 6 illustrate a modification, wherein a pair of stationary arms J, fixed to the framework and provided at their outer ends with the pivoted pieces K, is employed to support the magazine temporarily during its transfer. As before, the magazine frame C is moved pivotally about the center D, but in order to hold it in different angular positions with relation to the stationary arms J, I provide it with suitable detent mechanism, such for instance as the spring-pressed pin H mounted in the frame upright H¹ and adapted to engage one or another of the series of holes H² formed in the sides of the frame C. The operation of these parts will be readily apparent. The magazine frame is first tilted downwardly to its lowermost position in relation to the fixed arms J, and the operative magazine A is slid endwise therefrom onto and over the pivoted pieces K on the arms J. The frame C is again rocked until the vacant pair of grooves C¹⁰ is brought into position, when the magazine A is moved thereinto. By a reversal of the previously described operation, involving of course the shifting of the magazine frame to the corresponding positions, one of the other magazines A¹ or A² is removed from storage and transferred to operative position.

As previously stated, I have shown my invention only in preferred form and by way of example, and as applied to the specific kind of machine indicated. Obviously, however, many modifications and alterations therein, and in its mode of application, will suggest themselves to those skilled in the art, without departure from its scope.

Having thus described my invention, its construction and mode of operation, what I claim and desire to secure by Letters Patent of the United States, is as follows:

1. In a typographical machine, the combination of assembling devices, a supporting frame mounted so that it can occupy only one operative position with relation to the assembling devices, and a plurality of magazines carried by the supporting frame and each adapted when in use to occupy the same position therein, the said magazines being interchangeable with each other as to such position.

2. In a typographical machine, the combination of stationary assembling devices, a supporting frame mounted so that it can occupy only one operative position with relation to the assembling devices, and a plurality of magazines carried by the supporting frame, one in operative position and another in inoperative position therein, the second magazine adapted to be substituted

- for the first so as to be brought into operative relation to the assembling devices.
3. In a typographical machine, the combination of assembling devices, a supporting frame mounted so that it can occupy only one operative position with relation to the assembling devices, and a magazine supported in operative position by the frame, the said frame being provided with means to support said magazine in inoperative position when another magazine is in use, and the said supporting means being inactive when the first magazine is in operative position.
4. In a typographical machine, the combination of assembling devices, a supporting frame mounted so that it can occupy only one operative position with relation to the assembling devices, and a plurality of magazines carried by the frame and each adapted when in use to occupy the same position therein, the said magazines being interchangeable with each other as to such position, and the said frame being movable from its operative position in order to facilitate such interchange.
5. In a typographical machine, the combination of assembling devices, a supporting frame mounted so that it can occupy only one operative position with relation to the assembling devices, and a plurality of magazines carried by the frame and each adapted when in use to occupy the same position therein, the said magazines being interchangeable with each other as to such position, and the said frame being movable from its operative position in order to facilitate such interchange and provided with means for supporting the magazines during their interchange.
6. In a typographical machine, the combination of assembling devices, a supporting frame mounted so that it can occupy only one operative position with relation to the assembling devices, and a plurality of magazines carried by the frame and each adapted when in use to occupy the same position therein, the said magazines being interchangeable with each other as to such position, and the said frame being movable from its operative position in order to facilitate such interchange, together with means for supporting the magazines during their interchange.
7. In a typographical machine, the combination of a supporting frame, and a plurality of magazines carried thereby, the said magazines being independently removable from the frame in a rearward direction, and the said frame being mounted to be swung backwardly and downwardly from its operative position to facilitate such removal, and provided with means common to all the magazines for supporting them during their removal.

8. In a typographical machine, the combination of assembling devices, a supporting frame mounted so that it can occupy only one operative position with relation to the assembling devices, and a plurality of magazines carried by the frame and each adapted when in use to occupy the same position therein, the said magazines being interchangeable with each other as to such position and being mounted to be withdrawn rearwardly from the frame to permit such interchange. 70
9. In a typographical machine, the combination of a supporting frame mounted to be moved backwardly and downwardly from its operative position, and a plurality of magazines carried by said frame and adapted when in use to occupy the same position therein and interchangeable with each other as to such position, the said magazines being mounted to be withdrawn rearwardly from the frame to permit such interchange. 75
10. In a typographical machine, the combination of assembling devices, a supporting frame mounted so that it can occupy only one operative position with relation to the assembling devices, and a plurality of magazines carried by the frame and each adapted when in use to occupy the same position therein, the said magazines being interchangeable with each other as to such position and being mounted to be withdrawn rearwardly from the frame to permit such interchange. 80
11. In a typographical machine, the combination of assembling devices, a supporting frame mounted so that it can occupy only one operative position with relation to the assembling devices, and a plurality of magazines carried by the frame and each adapted when in use to occupy the same position therein, the said magazines being interchangeable with each other as to such position and being mounted to be withdrawn rearwardly from the frame to permit such interchange, together with means for supporting the magazines when withdrawn 85 from the supporting frame. 90
12. In a typographical machine, the combination of assembling devices, a supporting frame mounted so that it can occupy only one operative position with relation to the assembling devices, and a plurality of magazines carried by the frame and each adapted when in use to occupy the same position therein, the said magazines being interchangeable with each other as to such position and being mounted to be withdrawn rearwardly from the frame to permit such interchange, together with means carried by said frame for supporting the magazines when withdrawn therefrom. 95
13. In a typographical machine, the combination of a supporting frame, and a plurality of magazines carried thereby, and adapted to be interchanged with each other as to position, the said magazines being mounted to be withdrawn rearwardly from the frame to permit such interchange, together with means for supporting the magazines when withdrawn from the frame, the said supporting means being movable to 100 correspond to the different positions of the magazines in the frame. 110
14. In a typographical machine, the combination of a supporting frame, and a plurality of magazines carried thereby, and 115

4
adapted to be interchanged with each other as to position, the said magazines being mounted to be withdrawn rearwardly from the frame to permit such interchange, together with means carried by said frame for supporting the magazines when withdrawn therefrom, the said supporting means being movable to correspond to the different

positions of the magazines in the supporting frame.

In testimony whereof I have affixed my signature in presence of two witnesses.

JOHN R. ROGERS.
